TWO-CYCLE INTERNAL COMBUSTION ENGINE

Application filed December 20, 1930. Serial No. 503,824.

This invention relates to a two-cycle internal combustion engine, the general object of the invention being to greatly reduce the number of moving parts, to secure the maximum power with the minimum amount of fuel and to otherwise increase the efficiency of the engine, by providing means for compressing the charge in one cylinder and introducing it into another cylinder, where it is fired.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a longitudinal sectional view, with parts in elevation and parts broken away.

Figure 2 is a transverse sectional view.

Figure 3 is a view of the member 8.

Figure 4 is a view showing the chambers 13.

In these views, the numeral 1 indicates the cylinder block which contains the cylinders 2, each cylinder being of two diameters, with the larger lower diameter forming a compression chamber 3. A piston 4 is provided for each cylinder and the lower end of each piston is shaped to provide a compression cylinder 5 for the compression chamber 3. A depending part of each cylinder 2 forms a skirt 6 which projects into the combustion chamber and an apron 7 is formed in each compression cylinder 5. A member 8 is inserted in a recess in one side of the block and is held therein by a cover plate 9 which is bolted or otherwise fastened to the block, as shown at 10. Partitions 11, 12 and 12' form with the member 8 and portions of the cylinders 2 chambers 13, each of which has a port 14 connecting the lower part of the chamber with the interior of a cylinder, and partitions 15 form chambers 16 in the member 8. One of these chambers 16 is connected by a

port 17 with a compression chamber 3 and a port 18 connects one of these chambers 16 with the chamber 13. An inlet manifold 19 is connected by a port 20 with each compression chamber 3 and an exhaust manifold 21 is connected by a port 22 with the lower part of each cylinder 2. A crank shaft 23 is arranged in the crank case 24 and the cranks of said shaft are connected by the rods 25 with the pistons. Each pair of cranks is arranged at diametrically opposite points so that when a piston in one cylinder is in its lowest position, the piston in the next cylinder will be in its highest position.

From the foregoing it will be seen that when a piston is in its lowest position, the inlet port 20 will be uncovered so that the explosive mixture from the manifold can enter the compression chamber 3 and then as the piston moves upwardly, the compression piston 5 will first cover the inlet port and then the apron 7 will cover the port so that the port remains closed during the upward stroke of the piston. The mixture compressed in the chamber 3 will pass through the port 17 into chamber 16 and from said chamber 16, the compressed mixture will pass into the combustion space of the next cylinder as soon as the port 14 of said next cylinder is uncovered by the downwardly moving piston therein. The mixture compressed in the second cylinder will flow into the chamber 16 from the port 17 of said second cylinder and then pass through the port 18 into the chamber 13 and through the port 14 into the first cylinder when the piston of said first cylinder uncovers the port 14. The flow of the compressed gases into each cylinder will cause the exhaust gases to flow through the port 22 into the exhaust manifold 21 and the scavenging effect is increased by forming the top of each piston with a baffle 26. Thus I have eliminated the usual valves and their operating parts, as the pistons and the aprons 7 control the ports. The mixture being compressed and heated in one cylinder before being introduced into the combustion space of the next cylinder where it is still further compressed, causes the en-

100

gine to operate with the maximum efficiency with the minimum amount of fuel.

The usual ignition system including the spark plugs 27, may be used, though if the 5 mixture is compressed to an extent where combustion will be automatically produced, the ignition system may be eliminated.

It is further understood that injectors may be used in place of spark plugs 27, and that 10 the air manifold 19 may be designed for Diesel type of operation.

It is thought from the foregoing description that the advantages and novel features of the invention will be readily apparent.

15 It is to be understood that changes may be made in the construction and in the combination and arrangement of the several parts, provided that such changes fall within the scope of the appended claim.

20 What I claim is:—

An internal combustion engine comprising a cylinder block containing cylinders, each cylinder being of two diameters, the larger diameter being lowermost and forming a 25 compression chamber, a piston provided in each cylinder and having its lower end shaped to form a compression cylinder for the compression chamber, a depending portion on each cylinder forming a skirt projected into 30 the compression chamber, an apron formed in each compression cylinder, a member inserted in one side of the block, partitions formed with the member and portions of the cylinder to provide chambers, each of said 35 last named chambers having a port connecting the lower portion thereof with the interior of the cylinder, partitions constituting chambers in the member and one of the last named chambers having a port communicating with the compression chamber and another port connecting another of said 40 chambers with the chamber formed by the first named partition, an inlet manifold communicative with each compression chamber, 45 an exhaust manifold communicative with the lower portion of each cylinder, and a cover plate removably mounting the member in the block.

In testimony whereof I affix my signature.
